UNITED STATES PATENT OFFICE.

CHARLES S. ALTHOUSE, OF READING, PENNSYLVANIA.

DYEING.

1,349,867.

Specification of Letters Patent. Patented Aug. 17, 1920.

No Drawing.

Application filed June 24, 1920. Serial No. 391,466.

To all whom it may concern:

Be it known that I, CHARLES S. ALTHOUSE, a citizen of the United States, residing at Reading, in the county of Berks 5 and State of Pennsylvania, have invented certain new and useful Improvements in Dyeing, of which the following is a specification.

This invention relates to improvements in 10 the art of dyeing, and it pertains more particularly to the method of dyeing cotton goods a sulfur black.

In dyeing cotton goods black, and particularly in the case of hosey and like articles, it is particularly desirable to produce an intense and brilliant black, and to this end I have devised the present process or method.

In the common process of dyeing goods 20 of this character, the goods are first dyed, then subjected to a washing, and thereafter subjected to a finishing or what is termed a "softening" bath.

In my present invention my object is to 25 accomplish a particularly brilliant black, and also to produce a finished product in which the softening effect is intensified, and I accomplish this object by adding magnesium sulfate to the softening bath.

30 This softening bath usually consists of soluble oils or oil emulsions, and I find by actual practice that the introduction of magnesium sulfate to this bath will so affect the sulfur black that the result is a most brilliant and intense black, while the fabric is

rendered very materially softer than when the magnesium sulfate is not used.

In practice I have found that the use of magnesium sulfate in proportions of from one to ten per cent. will produce very satisfactory results, and also, that an excessive proportion of magnesium sulfate has not produced unsatisfactory results; while I have also discovered that the introduction of magnesium sulfate in any appreciable 45 quantity, into the softening bath commonly used in dyeing sulfur black, will materially increase the brilliancy of the black in the product.

The invention therefore resides in the introduction of magnesium sulfate into the softening bath.

I claim:

1. That step in the art of dyeing cotton goods sulfur black, which consists of introducing magnesium sulfate into the softening bath.

2. That step in the process of dyeing cotton goods sulfur black, which consists of subjecting the goods, after being dyed and washed, to a softening bath into which magnesium sulfate has been introduced.

3. A softening bath for black sulfur dyed cotton goods, containing magnesium sulfate.

4. A softening bath for black sulfur dyed 60 cotton goods, containing magnesium sulfate in substantially the proportions specified.

In testimony whereof I affix my signature.

CHARLES S. ALTHOUSE.
